UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

SAFETY DEVICE FOR LAMP-SIGNALS.

No. 801,364.

Specification of Letters Patent.

Patented Oct. 10, 1905.

Application filed February 19, 1904. Serial No. 194,339.

To all whom it may concern:

Be it known that I, FRED B. COREY, a citizen of the United States, residing at Schenectady, county of Schenectady, State of New York, 5 have invented certain new and useful Improvements in Safety Devices for Lamp-Signals, of which the following is a specification.

My invention relates to railway signal systems which are illuminated at night by lamps; 10 and the object of my invention is to eliminate the possibility of accidents occurring from the accidental extinguishing of a lamp.

Railway-signals are ordinarily illuminated at night by oil-lamps, which are liable to be 15 accidentally extinguished by a high wind or failure of the oil-supply or other similar cause. When the lamp is extinguished, an accident is very likely to result, since an engineer may fail to see the unlighted signal at all or may 20 take the chances of its being at "safety," knowing that he has the excuse that he was unable to see the unlighted signal.

In one aspect my invention consists in providing automatic means for stopping a train 25 in case a lamp is extinguished.

In another aspect my invention consists in the combination, with a signal and its lamp, of a thermostat exposed to the heat of the lamp and a device controlled by the thermostat located along the roadway and adapted to be 30 moved into a position to engage a device—such, for instance, as a valve—on a passing train.

My invention will best be understood by 35 reference to the accompanying drawing, in which—

L represents a lamp which lights the semaphore-signal A.

T represents a thermostat which is placed 40 so as to be heated by the lamp-flame, and consequently to be held in the position shown as long as the lamp is lighted. If the lamp is extinguished, however, the thermostat returns to a horizontal position and bridges 45 contacts t t. These contacts are in the circuit of the battery or other source of current B, to which is connected the stop device.

C is a magnet-coil or solenoid connected in the battery-circuit, the armature D of which 50 acts as a trip for the rod E, which is connected to the pivoted member F. When D is withdrawn by the energizing of coil C, rod E is free to fall and the pivoted member F is rotated into an upright position by the weight

W. Member F is disposed adjacent to the 55 rail R and is designed to strike a valve controlling the air-brakes on a passing train. The member F is normally held in an inoperative position, as shown, by the catch D; but if the lamp L becomes accidentally extinguished 60 thermostat T closes a circuit through battery B and tripping-coil C, releasing member F and allowing it to move into an upright position, so as to strike a valve on a passing train and bring it to rest if it at 65 tempts to pass the signal.

Switch S is provided to open the battery-circuit in the day-time, when the lamp is not lighted.

I do not desire to limit myself to the particular construction and arrangement of parts here shown, since changes which do not depart from the spirit of my invention and which are within the scope of the appended claims will be obvious to those skilled in the 75 art.

What I claim as new, and desire to secure by Letters Patent of the United States, is—

1. In combination, a railway-signal, a lamp for lighting said signal, a thermostat exposed 80 to the heat of said lamp, and a train-stopping device controlled by said thermostat.

2. In combination, a railway-signal, a lamp for lighting said signal, a thermostat exposed 85 to the heat of said lamp, an electric circuit controlled by said thermostat, a train-stopping device, and a magnet-winding included in said circuit and controlling said device.

3. In combination, a railway-signal, a lamp for lighting said signal, a thermostat exposed 90 to the heat of said lamp, a train-stopping device located along the roadway, and electromagnetically-operated means controlled by said thermostat for holding said device normally in an inoperative position.

4. In combination, a railway-signal, a lamp for lighting said signal, a thermostat exposed 95 to the heat of said lamp, an electric circuit controlled by said thermostat, a train-stopping device located along the roadway, a catch 100 for holding said device normally inoperative, and a tripping-coil in said circuit arranged to disengage said catch.

5. In combination, a railway-signal, a lamp for lighting said signal, a thermostat exposed 105 to the heat of said lamp, an electric circuit controlled by said thermostat, a train-stopping device, a magnet-winding included in

said circuit and controlling said device, and a switch for breaking said circuit independently of said thermostat.

6. In combination, a railway-signal, a lamp for lighting said signal, a thermostat exposed to the heat of said lamp, and a device controlled by said thermostat located along the roadway and adapted to be moved into a position to engage a passing train.
7. In combination, a railway-signal, a lamp for lighting said signal, a thermostat exposed to the heat of said lamp, an electric circuit controlled by said thermostat, a device located along the roadway and adapted to be moved into a position to engage a passing train, and a magnet-winding included in said circuit and controlling said device.

8. In combination, a railway-signal, a lamp for lighting said signal, a thermostat exposed to the heat of said lamp, an electric circuit controlled by said thermostat, a device located along the roadway and adapted to be moved into a position to engage a passing train, a catch for holding said device normally in an inoperative position, and a tripping-coil in said circuit arranged to disengage said catch. 20 25

In witness whereof I have hereunto set my hand this 17th day of February, 1904.

FRED B. COREY.
